CLAIM

The ornamental design for an ornamental illuminated lamp in the shape of a football, as shown.

DESCRIPTION

FIG. 1 is a front view of an ornamental illuminated lamp in the shade of a football showing my new design;

FIG. 2 is a back view thereof;

FIG. 3 is a side view (opposite side view is mirror image) thereof;

FIG. 4 is a top view thereof;

FIG. 5 is a bottom view thereof; and,

FIG. 6 is a perspective view thereof.
